United States Patent Office

Des. 226,655
Patented Apr. 10, 1973

226,655

TRAILER OR THE LIKE

James D. Ezell, 108 Pineland Circle,
Raleigh, N.C. 27612

Filed Feb. 22, 1971, Ser. No. 117,855

Term of patent 14 years

Int. Cl. D12—10

U.S. Cl. D14—3 E

fig. 1

Des. 226,655

fig.5

FIG. 1 is a perspective view of the trailer or the like showing my new design;

FIG. 2 is a top plan view of such design;

FIG. 3 is a side elevational view of the same;

FIG. 4 is a rear elevational view of such design; and

FIG. 5 is a front elevational view thereof.

I claim:

The ornamental design for a trailer or the like, as shown.
